[57] CLAIM

The ornamental design for a taco plate, as shown and described.

DESCRIPTION

FIG. 1 is a perspective view of a taco plate showing my new design;

FIG. 2 is a side elevational view thereof, the view from the opposite side being a mirror image;

FIG. 3 is an end elevational view thereof, the view from the opposite end being a mirror image;

FIG. 4 is a bottom view thereof;

FIG. 5 is a perspective view of a further embodiment thereof in which both end elevational views are identical to FIG. 3 of the first embodiment;

FIG. 6 is a bottom view of FIG. 5; and,

FIG. 7 is a side elevational view of FIG. 5, the view from the opposite side being a mirror image.

FIG. 1

FIG. 2

FIG. 3

FIG. 4

FIG. 7
